UNITED STATES PATENT OFFICE.

PHILIP G. PFEIL, OF CHICAGO, ILLINOIS.

WINDOW MOUNTING.

Application filed May 31, 1924. Serial No. 716,886.

This invention relates in general to building constructions, and has reference more particularly to an improved construction for mounting a window sash in its casing. 5 The invention belongs to that type of windows wherein the upper and lower sash are so mounted as to be capable of the usual vertical sliding movement in the casing guides, and also an inward swinging movement on one hinged edge of the sash so as to permit ready access to both sides of the glazing for cleaning. A typical example of this type of window, and one upon which my present invention is in the nature of an improvement, is shown in Letters Patent 10 No. 1,487,596 granted to me March 18, 1924. Among the objects sought by the present invention are, to provide a construction of sliding and swinging sash that will obviate 15 the canting and sticking of the slides to which the sash is hinged in their slideways and thus afford a freer and easier up and down sliding movement, to provide a hinge construction that will strongly hold the sash 20 against drooping or sagging when swung inwardly, to provide a construction wherein both sash shall be pivotally mounted in such a manner that they may both be swung inwardly to positions substantially normal to 25 the plane of the sash when closed, thereby permitting equally facile access to both sides of the sash for cleaning as well as affording maximum ventilation, when desired, through a practically unobstructed window 30 opening, to provide in a construction employing sliding and swinging sash improved weather stripping for rendering the sash substantially tight against cold air, rain and dust, to provide such construction 35 wherein the weather strips may be readily applied and removed without themselves requiring fastenings, to provide an improved combination stop and weather strip for co-operation with the free vertical edge of the 40 lower sash, to provide an improved parting strip which will permit the inward swinging 45 of the upper sash when lowered, to provide an improved weather strip for the free vertical edge of the upper sash, and, generally, 50 to provide a simple, improved and efficient window construction of the type mentioned which, as to the sash mountings by which the combined sliding and swinging movements are effected may be cheaply 55 and economically manufactured from sheet metal, and may be readily applied to any

standard construction of window casing and sash guides without requiring any substantial alteration thereof.

Other objects and attendant advantages 60 of the invention will be apparent to persons skilled in the art as the same becomes better understood by reference to the following detailed description, taken in connection with the accompanying drawings wherein I 65 have illustrated a practical and improved embodiment of the principle of the invention, and in which—

Fig. 1 is a front elevation of a window 70 casing and window employing upper and lower sash and embodying my present improvements;

Figs. 2 and 3 are vertical sections transverse to the plane of the window on the line 2—3 of Fig. 1 looking in the direction 75 indicated by the arrows; Fig. 2 showing the upper and lower sash in their respective closed positions, and Fig. 3 showing both sash in raised position;

Fig. 4 is an inner side elevation of the 80 left hand sash guide, viewing Fig. 1, with the sash removed, and showing the sheet metal slideways and slides in place therein, and also the sash counterweight pulleys and 85 cords, these latter attached to the slides which in turn are attached to the sash;

Fig. 5 is a substantially central vertical section through the window frame and the sash guides, broken out both lengthwise and widthwise, and showing the lower sash in 90 lowered position with the upper sash omitted;

Fig. 6 is a horizontal section on the line 95 6—6 of Fig. 1, showing both sash and their upper hinges in top plan view;

Fig. 7 is a horizontal section through the window frame, sash guides and both sash in lowered position, the section being taken in the plane of the line 7—7 of Fig. 5;

Fig. 8 is a sectional detail through one 100 upper corner of the upper sash on the line 8—8 of Fig. 1, and more particularly illustrating the hinge; and

Fig. 9 is a sectional detail on the line 9—9 of Fig. 1.

Figure 10 is a transverse sectional view 110 of the sash frame and channel retaining member disclosing the manner in which the weather strip is fixedly secured to the slide and prevented from sidewise and endwise movement.

Referring to the drawings, 11 designates

the sill, 12 the vertical side frame members and 13 the top bar of an ordinary window casing. 14 (Fig. 6) designates the usual pulley stiles forming the inner walls of the hollow side frame members 12 of the casing, within which latter the sash pulleys, weights and cords are usually accommodated. In my present construction the sash counterbalances are employed only on one side, since the sash are designed and adapted to swing inwardly from the opposite side.

To the inner faces of the pulley stiles 14 are attached the usual back strips 15 and parting strips 16 which form guideways for the upper sash 17. To the pulley stile 14 at the left, viewing Figs. 1 and 6, is also attached a front stop 18, the mating front stop on the other side being hinged to swing inwardly and more particularly hereinafter described, and 19 designates the lower sash.

To and extending full length of the sash guideway formed by the left hand pulley stile 14 and strips 15 and 16 is attached a sheet metal channel strip 21, and to the similar guideway formed by the pulley stile 14 and the strips 16 and 18 at the left is attached a similar sheet metal channel strip 22. These strips are clearly shown in Fig. 4 and constitute slideways for slides that are hinged to the upper and lower ends of the left hand sides of the upper and lower sash respectively.

As shown in Figs. 4 and 5, the pulley stile 14 at the left is slotted at 23, and the channel guide strips 21 and 22 are formed with registering slots 24 to accommodate the sash cords 25 and their pulleys 26, which latter are journaled in brackets 27 mounted on the inner wall of the vertical frame member 12, and 28 designates the usual counterweights. Slidably engaged with the channel strips 21 and 22, and at their longitudinal edges underlying the inwardly turned flanges of said channel strips, are upper and lower slides 29 and 31, respectively, one pair pertaining to the upper sash 17 and the other to the lower sash 19. Each slide 29 at its upper end is formed with an integral horizontally bent extension 32 of sector shape as shown by dotted lines in Fig. 6, and each slide 31 is formed at its lower end with a similar horizontal extension 33. The extensions 32 and 33 constitute one member of a sash hinge, the other member of which consists of angle strips 34 and 35 that are connected to the fixed members 32 and 33 by pivot pins 36 and 37 respectively. The hinge members 34 and 35 are secured to the upper frame bars of the sash by screws 38 as indicated in Figs. 1 and 8. As shown in Figs. 6 and 8, the hinge pivots 36 and 37 are located just inwardly of the planes of the inner sides of the sash so as to enable the latter, when swinging inwardly, to readily clear their vertical guideways; and as will be

observed from Fig. 6 the hinge pivots of one sash (the upper) are set further inwardly toward the center of the sash than are the pivots of the other, whereby it is possible to swing both sash inwardly to positions normal or at right angles to the plane of the window opening, as shown by dotted lines in Fig. 6. The fixed hinge leaves 32 are slotted, as shown at 32' in Fig. 6 to allow for the passage of the sash cords 25 therethrough. For greater stiffness and rigidity, the horizontal limbs of the hinge members 34 and 35 are folded back over and under the stationary hinge limbs 32 and 33, and by giving the rear edge of the latter the rounded or convex margins shown in Fig. 6, the inner folded edges of the swinging hinge members 34 and 35 are enabled to slide over the curved edges of the stationary hinge members.

By making each slide of each pair of slides 29 and 31 independent of the other and cooperative slide of that pair, the slides can be constructed to be substantially universally applicable to windows of various heights. Thus few different slides need be manufactured and kept on hand for windows of different heights. The hinge arrangement and construction will be substantially the same in every case. These features will be obvious from an inspection of the drawing.

The lower slide member 31 in the case of each sash is cut or slotted adjacent its upper end and a portion outwardly pressed to form a loop or bail 38 to which the lower end of the sash cord 25 is attached; and the lower end of the upper slide 29 in the case of each sash is formed with a similar transverse loop or bail 39, behind which the cord 25 extends. By reference to Fig. 7 it will be observed that the vertical outer edge of each sash is recessed or countersunk to seat the loops or bails 38 and 39.

My invention also preferably employs a novel weather strip feature that is associated with the channel guides 21 and 22 and the slides 29 and 30. This feature is perhaps most clearly shown in the cross-sectional view Fig. 7, wherein 41 designates the weather strip of angle form. One limb of this angle strip slidably underlies the rear flange of the channel guide strip 21, 22, while its other limb, which is preferably folded on itself to provide a double thickness of the metal fits into a longitudinal groove or rabbet in the outer edge of the sash. Each of these weather strips preferably extends the full height of the sash, substantially abutting at its upper and lower ends the hinge members of the sash. Hence, these weather strips of course partake of the rising and lowering movements of the sash, but they are held against following the edges of the sash during the swinging

movements of the latter by means of a pair of hooks 42 and 43, which are soldered at their bases to the slides 29 and 31 and embrace the inwardly projecting limbs of the weather strips, as clearly shown in Figs. 5 and 7.

The free vertical edge of the upper sash 17 is preferably equipped with a weather strip (not shown) attached to the inner face 10 of the stile 14 and formed with a tongue registering with a corresponding longitudinal groove 44 (Fig. 6) in the contacting edge of the sash. This weather strip, of course, extends only the length of the upper 15 sash, so that when the latter is fully lowered, its free edge is disengaged from the weather strip and may readily swing inwardly. To further permit this inward swinging movement of the lowered upper sash, the 20 lower half of the parting strip 16 is beveled off, as shown at 16' in Fig. 9, sufficiently to enable the free edge of the sash lying therebehind to clear the same.

The free edge of the lower sash 19 is 25 preferably equipped with an improved combination stop and weather strip, the structure of which is best shown in Figs. 6, 7 and 9. This comprises a molding strip 45 preferably of quadrant form in cross-section that is hinged at the inner front corner of the stile bar 14 as by ordinary upper and lower hinges 46, and has attached to its rear face a flat metal weather strip 47 terminating in an inwardly turned folded tongue 48 that 30 registers with a corresponding rabbet 49 in the free edge of the lower sash. This hinged stop and weather strip, of course, extends only the full height of the lower sash; and to swing the latter inwardly it is 35 first raised to clear the tongue 48 of the weather strip, the stop and weather strip are then swung outwardly to the dotted line position shown in Fig. 6, and by then fully lowering the lower sash the latter is free to 40 swing inwardly.

The described manner of, and means for, hinging the sash to the slides possesses several distinct advantages, as follows. Since the leaves of the hinges are horizontal and 45 extend substantially the full width of the slides, when the sash is raised and lowered a direct up and down thrust is imparted to the slides that lie wholly between their vertical edges, and hence there is no tendency 50 to cant the slides in their slideways such as occurs where the hinges are offset relatively to one edge of the slide. Again, by causing the pivoted hinge leaf to embrace the fixed hinge leaf, the sash when opened is stoutly 55 held against sagging or drooping. Again, by simply removing the screws attaching the pivoted hinge leaves to the sash, the latter can be easily removed from the casing whenever required as, for instance, to replace a 60 broken glass, without requiring the with- 65

drawal of the sash mountings from their guideways.

While I have herein shown and described a practical embodiment of the invention well adapted to effectuate the stated purposes 70 and objects thereof, it is manifest that the specific details of structure may be considerably varied without departing from the principle of the invention or sacrificing any of the advantages thereof. Also, while I 75 have described the sash as swinging inwardly, it is manifest that by merely locating the pivots on the other or rear sides of the hinge leaves, and suitably reversing the parting strip and stops at the opposite 80 edge, the sash may be made to open outwardly. Hence, I do not limit the invention to the precise construction herein disclosed for purposes of illustration, but reserve all such variations and modifications 85 as fall within the spirit and purview of the appended claims.

I claim—

1. In a window construction of the character described, the combination of a casing 90 formed with sash guiding grooves, a sheet metal channel strip attached to the base of one of said grooves, a sash engaged with one of said grooves, sheet metal slide members mounted in said channel strip and having 95 integrally formed and horizontally extending hinge leaves overlapping the upper and lower edges of the sash, and sheet metal hinge leaves having portions forming bearing surfaces for opposite sides of the first said 100 hinge leaves, secured to said sash and having horizontal limbs overlapping the upper and lower edges of the sash and pivoted to the first said hinge leaves.

2. In a window construction of the character described, the combination of a casing formed with sash guiding groove, a sheet metal channel strip attached to the base of said groove, a sash provided with independently adjustable sheet metal slide members, 105 said slide members being slidingly mounted in said channel strip and formed with integral horizontally extending hinge leaves overlapping the upper and lower edges of the sash, and hinge leaves attached to said sash and formed with integral folded horizontal limbs overlapping the upper and lower edges of the sash and pivoted to and 110 embracing said first-named hinge leaves.

3. In a window construction of the character described, the combination of a casing formed with a sash guiding groove, a channel strip attached to the base of said groove, upper and lower independently adjustable slide members mounted in said channel strip and formed with integral horizontally extending hinge leaves overlapping the upper and lower edges of the sash and of a width 120 substantially coextensive with the edges of the sash, and angle hinge leaves formed with 125

vertical limbs attached to one face of the sash and horizontal limbs overlapping the upper and lower edges of the sash, said horizontal limbs being folded at one edge to embrace both top and bottom of the first said hinge leaves, and a pivot pin passing through each of said horizontal limbs, and each of the first said hinge leaves.

4. In a window construction of the character described, the combination of a casing formed with sash guiding grooves, channel strips attached to the bases of said grooves on one side of said casing, upper and lower sashes engaged with said grooves, upper and lower independently adjustable slide members for windows of different sizes mounted in each of said channel strips and formed with flat horizontally extending hinge leaves having one edge of sector shape overlapping the upper and lower edges of the sashes, hinge leaves attached to said sashes and formed with horizontal limbs overlapping the upper and lower edges of the sashes, and with portions embracing and engaging two sides of said flat hinge leaves, and vertical pivot pins connecting co-operating pairs of said hinge leaves, the pivot pins of said upper sash being inwardly offset from said grooves at a greater distance than the corresponding pivot pins of said lower sash.

5. In a window construction, a casing having a sash guiding groove, a slide retaining guide member in said groove, a pair of slides having hinge leaves connected thereto within said guide member and adapted to be hinged to the upper and lower edges of a sash, a sash having a rabbet in a vertical edge thereof, and a weather strip independent of said slides having a portion adapted to be received in said rabbet and a portion slidably engaged with said guide member and having its ends abutting the opposed faces of said hinge leaves, whereby upon raising and lowering movements of the sash said weather strip will follow said slides.

6. In a window construction in combination, a slide receiving and retaining member adapted to be fixedly positioned in a sash receiving frame, a pair of independently adjustable slides each adapted to be received and retained by said member, said lower slide terminating in a bale to which the sash cord is adapted to be fastened, said upper slide portion terminating at its lower extremity in a cutout portion constituting a loop behind which the sash cord extends.

7. In a window construction of the character described, the combination of a casing formed with sash guiding grooves, a sash engaging with said grooves and formed with a rabbet in one vertical edge thereof, a slide member mounted in one of said grooves and hinged to said sash, a weather strip independent of said slide member and slidably mounted in said groove and having a limb

portion occupying the rabbet in said sash when the latter is closed, means for engaging the limb portion of the weather strip to retain the weather strip in said groove when the sash is open, and means for confining said weather strip endwise whereby it is caused to follow the rising and lowering movements of said sash.

8. In a window construction of the character described, the combination of a casing formed with sash guiding grooves, a channel strip attached to the base of one of said grooves, a sash engaged with said grooves and formed with a rabbet in one vertical edge thereof, a slide member mounted in said channel strip and hinged to said sash, and an angle weather strip having one limb thereof slidably mounted in said channel strip and its other limb projecting into and occupying the rabbet of said sash when the latter is closed and means fixedly secured to the slide adapted to overlie and tightly engage the rabbet receiving portion of the weather strip to retain it in place when the sash is open.

9. In a window construction of the character described, the combination of a casing formed with sash guiding grooves, a channel strip attached to the base of one of said grooves, a sash engaged with said grooves and formed with a rabbet in one vertical edge thereof, a slide member mounted in said channel strip and hinged to said sash, an angle weather strip having one limb thereof slidably mounted in said channel strip and its other end projecting into and occupying the rabbet of said sash when the latter is closed, and means retaining said weather strip in place when the sash is opened, said means comprising a hook shaped element fixedly secured to the slide and tightly engaging the rabbet receiving portion of the weather strip.

10. In a window construction of the character described, the combination of a casing formed with sash guiding grooves, a channel strip attached to the base of one of said grooves, a sash engaged with said grooves and formed with a rabbet in one vertical edge thereof, upper and lower slide members mounted in said channel strip and formed with horizontal hinge leaves overlapping the upper and lower edges of said sash and pivotally connected to the latter, and a weather strip slidably mounted in said channel strip and projecting into and occupying the rabbet of said sash when the latter is closed, said weather strip being confined endwise by and between said hinge leaves whereby it is caused to follow the rising and lowering movements of said sash.

11. In a window construction of the character described, the combination of a casing formed with sash guiding grooves, a channel strip attached to the base of one

- of said grooves, a sash engaged with said grooves and formed with a rabbet in one vertical edge thereof, upper and lower slide members mounted in said channel strip and formed with horizontal hinge leaves overlapping the upper and lower edges of said sash and pivotally connected to the latter, an angle weather strip having one limb thereof slidably mounted in said channel strip and its other limb projecting into and occupying the rabbet of said sash when the latter is closed, said weather strip being confined endwise by and between said hinge leaves, and a hook attached to said channel strip and adapted to engage the rabbet receiving portion of the weather strip to confine the latter in place when the sash is open. 70
12. In combination with a window casing and a sash, a sash guiding groove in said casing, a slide retained in said groove and hinged to said sash, a rabbet in said sash, a weather strip positioned in said rabbet, and means adapted to hold said weather strip against movement with the sash when the sash is swung about its hinge, said means being fixedly attached to the slide and adapted to engage the rabbet receiving portions of the weather strip. 75
13. In window construction of the character described, a frame having a sash receiving groove, a sash having one vertical edge slidably received in said groove, hinge members secured at opposite ends of said vertical edge, a pair of slides retained in said groove and cooperatively hinged to said hinge members, whereby said sash may be raised and lowered vertically and swung out of normal position on said hinges, a weather strip slidable with said sash when in normal position, and means adapted to retain said strip in relatively fixed position to said frame when said sash is swung out of normal position, said means comprising a hook shaped element fixedly secured to the slide and adapted to engage the sash receiving portion of the weather strip. 80
14. In a window construction, the combination of a window frame, a sash hinged at one vertical edge thereof to said frame, a stop for the free vertical edge of said sash vertically pivoted to the opposite vertical edge of said frame, and a weather strip attached to said stop. 85
15. In a window construction, the combination of a window frame, a sash mounted in said frame with capacity of both vertical sliding movement and lateral swinging movement relatively thereof, a stop for the free vertical edge of said sash vertically pivoted to the vertical edge of said frame engaged by the free edge of said sash, and a weather strip attached to said stop. 90
16. In a window construction, the combination of a window frame, a sash mounted in said frame with capacity of both vertical sliding movement and lateral swinging movement relatively thereof, said sash formed with a rabbet in its free vertical edge, a stop for the free vertical edge of said sash vertically pivoted to the vertical edge of said frame engaged by the free edge of said sash, and a weather strip attached to said stop. 95
17. In construction of the character described, a window frame, a sash stop pivoted thereto for movement into and out of engagement with a sash, and a weather strip connected to said stop for swinging movements therewith. 100
18. In construction of the character described, a window frame, a sash stop pivoted thereto for movement into and out of engagement with a sash in said frame, and means adapted to cooperate with a sash in said frame to retain said stop in sash engaging position. 105
19. In combination, a sash stop adapted to be pivotally engaged with a sash frame and a weather strip connected for pivotal movement therewith. 110
20. In a window construction, the combination of a casing formed with front and rear sash guiding grooves, lower and upper sashes engaged with said front and rear guiding grooves respectively, means for mounting said sashes at one vertical edge thereof with capacity of both sliding and swinging movements, and a parting strip on said casing between the free vertical edges of said sashes, the portion of said parting strip lying opposite the lower sash being beveled whereby to permit the free edge of said upper sash, when lowered, to swing past the same. 115
21. In a window construction, upper and lower sashes, means for mounting said sashes at one vertical edge thereof for swinging movements, and a parting strip between the sashes constructed and arranged to retain the upper sash against swinging movements when in an upper position and to release said upper sash for swinging movements when in a lowered position. 120
22. In a window construction, upper and lower sliding sashes, means for pivotally mounting said sashes each at one side edge for swinging movements, and a parting strip constructed and arranged to retain the upper sash against swinging movements when in an upper position and to release said upper sash for swinging movements when lowered. 125
23. In a window construction, a casing, upper and lower sashes slidably mounted therein, means pivotally mounting said sashes at one sliding edge of each whereby they may be swung thereabout, and means connected to said casing constructed and ar- 130

ranged to retain the upper sash against swinging movements when in an upper position and to release said upper sash for swinging movements when lowered.

5 24. In window construction, a parting strip having a deep portion adapted to retain and guide a window sash and a portion of less depth adapted to permit a sash to swing thereby.

10 25. In a window construction, in combination, a slide receiving and retaining member adapted to be fixedly secured in a sash receiving frame, a pair of slides each adapted to be received and retained by said member and independently and slidably adjustable in said member for engaging the upper and lower edges of sashes of different sizes, substantially as described.

20 26. In a window construction of the character described, the combination of a casing formed with sash guiding grooves, a channel strip attached to the base of one of said grooves, a sash engaged with one of said grooves, independently adjustable slide 25 members mounted in said channel strip and adapted to engage the upper and lower por-

tions of sashes of different sizes, said slide members having horizontally extending hinge leaves overlapping the upper and lower edges of the sash, and hinge leaves secured to the sash, and having horizontal limbs overlapping the upper and lower edges of the sash, and pivoted to and bearing upon said first-mentioned leaves.

27. In a window construction, a casing having a sash guiding groove, a sash engaged within said groove and formed with a rabbet in one vertical edge thereof, a slide member mounted in said groove and hinged to said sash adjacent the upper and lower edges thereof, a weather strip slidably mounted in said groove and having a limb portion occupying the rabbet in said sash when the latter is closed, and means for engaging the limb portion of the weather strip to retain the weather strip in said groove when the sash is swung on said hinges to an open position, said weather strip being confined between said hinges for vertical rising and lowering movements with said sash.

P. G. PFEIL
